EVAPORATOR STRUCTURE IN REFRIGERATION APPARATUS

Jules N. Saler, Springfield, Mass., assignor to Westinghouse Electric Corporation, East Pittsburgh, Pa., a corporation of Pennsylvania

Application December 13, 1951, Serial No. 261,443

6 Claims. (Cl. 62—115)

1

This invention relates to refrigeration apparatus and, more particularly to means for rapidly and effectively defrosting such apparatus.

It is an object of this invention to provide an improved refrigerating and defrosting system for selectively refrigerating and defrosting a refrigerant evaporator.

It is another object of this invention to provide a novel evaporator structure for a refrigerating and defrosting system.

These and other objects are effected by the invention as will be apparent from the following description and claims taken in connection with the accompanying drawings, forming a part of this application, in which:

Fig. 1 is a top plan view of the evaporator structure employed in this invention;

Fig. 2 is a rear elevation view of the evaporator structure;

Fig. 3 is an end elevation view of the evaporator structure;

Fig. 4 is a vertical, enlarged, cross-section view of the evaporator structure taken along the lines IV—IV of Fig. 2; and

Fig. 5 is a diagrammatic view of a refrigerating and defrosting system constructed in accordance with this invention.

Referring to the drawings, the numeral 10 designates generally a refrigerant evaporator structure of box-like configuration having an opening 12 in the front thereof for the reception of ice trays (not shown) and foods to be frozen or cooled to a low temperature. The evaporator structure 10 is adapted to be mounted within an insulated cabinet structure (not shown) of any suitable construction.

The evaporator structure 10 is of sectional or composite construction and consists of an L-shaped portion 14 forming the top and back walls of the evaporator structure and a U-shaped portion 16 forming the bottom and side walls of the evaporator. The L-shaped portion 14 is constructed of superimposed metal sheets 18 and 20, portions of which sheets are embossed to form refrigerant passages between the sheets. After forming, these sheets are secured together in any suitable manner such as by welding or brazing. Formed within the back wall portions of the L-shaped evaporator portion 14 is an inlet passage 22. Both evaporator sheets 18 and 20 are struck inwardly forming the refrigerant passage 22 to provide a recess on the exterior surface of the evaporator back wall for the reception of an electric heating element 24, the purpose of which will hereinafter be described. The inlet passage 22 extends along the bottom edge of the evaporator back wall, up the side edge thereof and communicates with an upper portion of a storage vessel 26 likewise formed by and between the

2

back wall portions of the L-shaped sheets 18 and 20. A pair of outlet passages 28 and 30 communicate with upper and lower portions, respectively, of the storage vessel 26 and are joined at a point 32 near the upper edge of the storage vessel 26. The upper outlet passage 28 is provided with a restriction 34 which may be formed by crimping the passage 28 or by placing a fixed restriction within the passage 28 before assembling sheets 18 and 20. The lower outlet passage 30 continues along the upper edge of the evaporator back wall and communicates with a sinuous refrigerant passage 36 formed by and between the top wall portions of the L-shaped sheets 18 and 20.

The U-shaped portion 16 of the evaporator structure 10 is likewise formed by two superimposed metal sheets 37 and 38 having refrigerant flow passages formed therebetween, which, for the sake of simplicity, have been shown as parallel passages 39 extending from the upper portion of one side wall downwardly, across the bottom wall, and upwardly to the upper portion of the opposite side wall. The refrigerant passages 39 are connected at one end by an inlet header 40 and at the other end by a suction or outlet header 42.

The two portions 14 and 16 of the evaporator structure 10 are operatively connected to form a continuous refrigerant flow passage by a conduit 44 connecting the outlet end 46 of the sinuous passage 36 with the inlet header 40 on the side wall of the U-shaped evaporator portion 16.

As in a conventional refrigerating system, apparatus is provided for supplying refrigerant to and withdrawing refrigerant from the evaporator structure 10. As shown in Fig. 5, this apparatus includes a motor-driven compressor 48, a condenser 50, a hot gas conduit 52 for conveying refrigerant compressed by the compressor 48 to the condenser 50, a capillary tube 54 for conveying refrigerant condensed by the condenser 50 to the inlet passage 22 of the evaporator structure 10, and a suction or return conduit 56 for conveying refrigerant from the outlet header 42 on the evaporator structure 10 to the compressor 48. As shown in Fig. 5, the return conduit 56 is soldered to or otherwise arranged in heat exchange relationship with portions of the capillary tube 54 and the hot gas line 52.

Power to operate the refrigerating and defrosting system is provided by electric supply lines L₁ and L₂ under the control of a thermostatic switch 58 connected in series with the leads 60, 62 and 64 supplying power to the motor compressor 48. Switch 58 is actuated in response to pressure changes within a temperature-sensitive bulb 66 secured to a portion of the evaporator structure 10 to energize and deenergize the motor compressor 48 to maintain the desired tempera-

ture of the evaporator structure 10, as is well understood. Current to energize the electric heating element 24 is likewise derived from lines L₁ and L₂ through lead 60, switch 58, leads 62, 68 and 70, through switch 72 and lead 74. It will be noted that the thermostatic control switch 58 is also in series with the supply circuit for the heater 24 and, therefore, the heater may be energized by the switch 72 only during those periods when the motor compressor 48 is energized.

Referring to Fig. 5, the operation of the improved refrigerating and defrosting system is as follows: During a refrigerating operation, the switch 72 is open and heater 24 is deenergized. The refrigerant from the compressing and condensing apparatus is conveyed through capillary tube 54 and enters the evaporator structure 10 through inlet passage 22. This refrigerant, the major portion of which is in a liquid state, flows into and floods or completely fills storage vessel 26, outlet passages 28 and 36 and flows into passage 36 in the top wall of the evaporator structure 10. Partial evaporation of the liquid refrigerant takes place in passage 36 and the resulting mixture of liquid and gas flows through connecting conduit 44 and header 40 into the refrigerant passages 39 of the U-shape portion 16 of the evaporator structure. As the refrigerant absorbs further heat from the food stuffs in the evaporator structure 10 and the surrounding air, it is converted entirely to gas which passes through the outlet header 42 and is conveyed back to the compressing and condensing apparatus by the return conduit 56.

During the refrigerating operation, any gaseous refrigerant which may be conveyed to or generated in the storage vessel 26 will escape through the upper outlet passage 28 and will be carried through the remaining refrigerant passages by the liquid refrigerant flowing therethrough. The restriction 34 in the outlet passage 28 is of sufficient size to permit the escape of all gaseous refrigerant trapped in the storage vessel during the refrigerating operation.

Due to the fact that the evaporator structure 10 is maintained at a temperature below 32° F., frost will collect thereon and must be removed to ensure efficient operation of the system. The removal of frost is effected by closing switch 72 to energize heater 24 which applies heat to the refrigerant flowing through inlet passage 22 of the evaporator structure 10. Since the heater 24 is so located as to apply heat to the refrigerant flowing through the system, it is desirable that the heater be energized only during a running period of the compressor 48. As previously noted, this condition of operation is effected by having the thermostatic switch 58 in series with the supply circuit of the heater 24. Should the switch 72 be closed during a shutdown period of the compressor 48, defrosting will merely be delayed until the next running period of the compressor 48 as controlled by the thermostatic switch 58 and its associated temperature-sensitive bulb 66.

The heat applied to the refrigerant flowing through inlet passage 22 vaporizes a major portion of this refrigerant and increases the quantity of gas in the storage vessel 26. Because of the restriction 36 in the upper outlet passage 28, only a portion of this gas is permitted to escape from the storage vessel 26, whereupon the pressure in the storage vessel 26 rises sufficiently to force the liquid refrigerant contained therein out through the lower outlet passage 30 and into the remaining refrigerant flow passages 36 and

39 in the evaporator structure 10. The storage vessel 26 contains sufficient liquid refrigerant to flood the remaining refrigerant flow passages 36 and 39 as well as the headers 40 and 42 of the evaporator 10 and cause some liquid refrigerant to be spilled over into the return conduit 56. A portion of the liquid refrigerant in return conduit 56 is vaporized by the heat derived through the heat exchanger between the return conduit 56 and the capillary tube 54 and the remaining liquid is vaporized by heat derived through the heat exchanger between the return conduit 56 and the hot gas line 52. This vaporization of liquid refrigerant returning to the compressor 15 causes an increase in the overall pressure in the lower pressure side of the refrigerating system and materially aides in the defrosting operation. The major defrosting action is attained, however, by the condensation of the hot gaseous refrigerant issuing from the heated portion of the inlet passage 22. This hot gas is forced through the various refrigerant passages in the evaporator structure 10 and, in condensing, gives up heat to the wall portions of the evaporator 10 to melt the frost which has collected thereon. The refrigerant thus condensed is revaporized in the return conduit 56 by the heat exchangers between the return conduit 56 and the capillary tube 54 and the hot gas line 52.

30 When defrosting is complete, the switch 72 is opened to deenergize the heater 24 and permit the system to return to refrigerating operation.

If desired, automatic control means may be provided for closing and opening switch 72 in response to the various conditions indicating the collection of frost and the absence of frost on the evaporator. Such a control is described and claimed in U. S. Patent No. 2,595,967, granted May 6, 1952 to Graham S. McCloy and assigned to the assignee of the present invention.

It will be apparent from the foregoing that this invention contemplates the construction of a refrigerating and defrosting system in which a storage vessel is formed by and between the superimposed sheets of the evaporator structure for the purpose of collecting and discharging liquid refrigerant. This construction is economical and permits of ease of assembly as compared to prior refrigerating and defrosting systems wherein the storage vessel was formed independently of the other elements of the system. It will further be noted that the novel arrangement of outlet passages from the storage vessel insures positive discharge of the liquid contents of the vessel during defrosting and yet allows the vessel to collect a maximum amount of liquid refrigerant during the refrigerating operation.

While I have shown my invention in but one form, it will be obvious to those skilled in the art that it is not so limited, but is susceptible of various changes and modifications without departing from the spirit thereof.

What I claim is:

1. In a refrigerating and defrosting system, the combination of a refrigerant evaporator comprising superimposed sheets, first and second refrigerant passages each having inlet and outlet ends and formed by and between said evaporator sheets, a compressor, a condenser, first conduit means for conveying compressed refrigerant from said compressor to said condenser, second conduit means including a flow impeding device for conveying refrigerant condensed by said condenser to the inlet end of said first refrigerant passage, third conduit means for conveying

refrigerant from the outlet end of said second refrigerant passage to said compressor, said third conduit means having a portion thereof arranged in heat exchange relationship with the refrigerant compressed by said compressor, a storage vessel formed by and between said evaporator sheets, said first refrigerant passage having the outlet end thereof communicating with said storage vessel, a first outlet passage communicating at one end with a lower portion of said storage vessel and at its other end with the inlet of said second refrigerant passage, a second outlet passage communicating at one end with an upper portion of said storage vessel and at its other end with said first outlet passage, said second outlet passage having a restriction therein, the construction and arrangement being such that liquid refrigerant accumulates in said storage vessel during refrigerating operation of said system, and means for applying heat to the refrigerant flowing through said first refrigerant passage to vaporize at least a portion of said refrigerant to increase the pressure in said storage vessel whereby the refrigerant liquid contained therein is forced out of said vessel through said lower outlet passage, said storage vessel containing sufficient refrigerant liquid to flood said second refrigerant passage and spill over into said third conduit means.

2. In a refrigerating and defrosting system, the combination of a refrigerant evaporator comprising superimposed sheets, first and second refrigerant passages each having inlet and outlet ends and formed by and between said evaporator sheets, a compressor, a condenser, first conduit means for conveying compressed refrigerant from said compressor to said condenser, second conduit means including a flow-impeding device for conveying refrigerant condensed by said condenser to the inlet end of said first refrigerant passage, third conduit means for conveying refrigerant from the outlet end of said second refrigerant passage to said compressor, a storage vessel formed by and between said evaporator sheets, said first refrigerant passage having the outlet end thereof communicating with said storage vessel, said second refrigerant passage having the inlet end thereof communicating with said storage vessel, the construction and arrangement being such that liquid refrigerant accumulates in said storage vessel during a refrigerating operation of said system, and means including a heater arranged in heat exchange relationship with said first refrigerant passage for heating and discharging the contents of said storage vessel into said second refrigerant passage to effect defrosting of said evaporator.

3. In a refrigerating and defrosting system, the combination of a refrigerant evaporator comprising superimposed sheets, first and second refrigerant passages each having inlet and outlet ends and formed by and between said evaporator sheets, a compressor, a condenser, first conduit means for conveying compressed refrigerant from said compressor to said condenser, second conduit means including a flow-impeding device for conveying refrigerant condensed by said condenser to the inlet of said first refrigerant passage, third conduit means for conveying refrigerant from the outlet end of said second refrigerant passage to said compressor, a storage vessel formed by and between said evaporator sheets, said first refrigerant passage having the outlet end thereof

communicating with said storage vessel, a pair of outlet passages communicating respectively with upper and lower portions of said vessel, said upper outlet passage having a restriction therein, said second refrigerant passage having the inlet end thereof communicating with said vessel outlet passages, the construction and arrangement being such that liquid refrigerant accumulates in said storage vessel during refrigerating operation of said system, means including a heater arranged in heat exchange relationship with said first refrigerant passage for heating and discharging the contents of said storage vessel into said second refrigerant passage to effect defrosting of said evaporator, said storage vessel containing sufficient refrigerant liquid to flood said second refrigerant passage and spill over into said third conduit means, and means for vaporizing the refrigerant liquid spilled into said third conduit means.

4. A defrostable refrigerant evaporator unit comprising a pair of superimposed L-shaped sheets adapted to form the top and back walls of a storage compartment, a refrigerant storage

25 vessel formed by and between the back wall portions of said sheets, an inlet passage and a pair of outlet passages for said vessel, said passages being formed by and between said sheets, said outlet passages communicating respectively with upper and lower portions of said vessel,

30 a sinuous passage formed by and between said L-shaped sheets, at least the major portion of said sinuous passage lying in the top wall portion of said sheet, said sinuous passage having the inlet end thereof connected to said storage vessel outlet passages, and an electric heating element arranged in heat transfer relation with said inlet passage.

5. A defrostable refrigerant evaporator unit comprising superimposed sheets, at least a portion of said sheets lying in a substantially vertical plane, a storage vessel formed by and between the vertical portions of said sheets, a refrigerant inlet passage and a pair of outlet passages for said vessel, said passages being formed by and between said sheets, said outlet passages communicating respectively with upper and lower portions of said storage vessel, a fourth refrigerant passage formed by and between said sheets, said fourth passage having the inlet end thereof connected to said pair of outlet passages, and an electric heater arranged in heat transfer relation with said storage vessel inlet passage.

6. A defrostable refrigerant evaporator unit comprising superimposed sheets, at least a portion of said sheets lying in a substantially vertical plane, a storage vessel formed by and between the vertical portions of said sheets, a refrigerant inlet for said vessel, a pair of outlet passages for said vessel, said passages being formed by and between said sheets, said outlet passages communicating respectively with upper and lower portions of said storage vessel, said upper outlet passage being formed with a restriction therein, and a third refrigerant passage formed by and between said sheets, said third passage having the inlet end thereof connected to said pair of outlet passages.
